UNITED STATES PATENT OFFICE.

RAYMOND C. MINER, OF FAITH, SOUTH DAKOTA, ASSIGNOR, BY MESNE ASSIGNMENTS,
OF ONE-HALF TO GEORGE GREGORY, OF GLENDALE, MONTANA.

PENCIL-SECURING HOLDER.

1,144,426.

Specification of Letters Patent. Patented June 29, 1915.

Application filed December 8, 1913. Serial No. 805,437.

To all whom it may concern:

Be it known that I, RAYMOND C. MINER, a citizen of the United States, residing at Faith, in the county of Meade and State of South Dakota, have invented certain new and useful Improvements in Pencil-Securing Holders, of which the following is a specification.

This invention relates to improvements in pencil securing holders, and has for its object to provide a clip form of holder adapted to be mounted upon a pencil or pen for use in quickly and easily securing the same in the pocket, or the like, of the user.

An advantage of my invention is that the same is arranged to permit easy insertion of cloth forming a pocket or the like, and placing the pen or pencil therein. The devices now in use for a similar purpose require some manipulation of the clip portion in applying the same to the cloth of the pocket, whereas, as stated, my device may be readily inserted and will automatically engage the same and secure the pen thereto against accidental removal, while permitting comparatively easy intentional removal when so desired. These and other objects will be set forth in the following specification and accompanying drawing, in which;

Figure 1 is a side elevation of a pencil showing my device applied thereto; Fig. 2 is a view similar to Fig. 1 taken at right angles thereto; Fig. 3 is a side elevation of a blank adapted to be bent into form to comprise my device; Fig. 4 is a transverse section taken along the line 4—4 of Fig. 1, and Fig. 5 is a side elevation showing my invention slightly modified to be applied to a pencil protecting device.

Like numerals refer to like elements throughout the drawings.

10 designates a conventional form of pencil to which is shown applied, one embodiment of my device in operative position, generally designated by the numeral 11, and comprising a body portion 12, bent into a substantially cylindrical form of slightly less diameter than that of the pencil 10, so that insertion of the latter in the cylindrical portion will operate to spread the side thereof, thereby increasing the frictional contact of the body portion 12 on the sides of the pencil. I have shown this body portion as apertured at 12^a, thereby forming three

strips 12^b, although it is obvious that these 55 apertures may be omitted if so desired.

An arm 13 is bent outwardly from the body portion at 12^a and then substantially parallel therewith and spaced therefrom, as clearly shown in Fig. 1. This arm 13 is 60 provided with the reversely bent portion 14, which in turn terminates in the looped end 14^a, at its extremity. This reversely bent portion 14 comprises a spring portion, the arm 13 being formed of suitable metal 65 or the like. I preferably form this arm 13 of flattened shape so that the name or initials of the user, or other suitable matter, may be engraved or inscribed thereon. The spring portion 14 is preferably arranged at 70 an angle with respect to the central of strips 12^b with which it normally yieldingly contacts, as clearly shown in Fig. 1. This angular disposition of the arm 14 with the body portion 12 permits the cloth of a pocket 75 or the like to readily slide therebetween when the pencil is placed in the pocket, and forcing downwardly thereof will cause the cloth to separate the spring arm 14 from its contact with the strip 12^b. The latter, by 80 means of its spring construction and angular arrangement, will press against the cloth and hold the same tightly against the body portion 12, and my device will thereby prevent accidental dropping out or loss of 85 the pencil or pen. The looped or enlarged end 14^a, presenting a rounded surface against the cloth, will permit the disengagement of the holder from the pocket upon sufficient pull being applied to the pencil to 90 remove the same.

While I have shown and described my improved device with more or less particularity, I do not wish to be restricted to such showing or description beyond the scope of 95 the appended claims.

What I claim is:—

1. A securing clip comprising a body portion and a securing portion integral with said body portion, said last-named portion 100 comprising an arm reversely bent with respect to said body portion and spaced therefrom, said arm having the end portion thereof reversely bent toward the point of attachment of said arm on said body portion 105 to form a spring member positioned between said arm and said body portion, the extremity of said spring member being arranged to

normally make a yielding contact with said body portion.

2. A securing clip comprising a body portion and a securing portion integral with said body portion, said last-named portion comprising an arm reversely bent with respect to said body portion and spaced therefrom, said arm having the end portion thereof reversely bent toward the point of attachment of said arm on said body portion to form a spring member positioned between said arm and said body portion, the extremity of said spring member terminating in a looped end arranged to normally make a yielding contact with said body portion.

3. A securing clip comprising a body portion and a securing portion integral with said body portion, said last-named portion comprising an arm reversely bent with respect to said body portion and spaced therefrom, said arm having the end portion thereof reversely bent toward the point of attachment of said arm on said body portion.

4. A securing clip comprising a body portion having the edges thereof bent to form a cylinder open along one side, an arm extending substantially parallel to the axis of said cylinder and spaced from said body portion, and a spring member extending from said arm and located between said arm and said body portion with the extremity thereof normally contacting with said body portion, all of said parts being integrally formed.

In testimony whereof, I have subscribed my name.

RAYMOND C. MINER.
